COSMETIC CONTAINER UNIT

Morton A. Carabel, Los Angeles, and Woodrow S. Wilson,
Pasadena, Calif.

Application September 30, 1955, Serial No. 38,191

Term of patent 14 years

(Cl. D86—10)

FIG.-1-

Fig. 1 is an isometric view of a cosmetic container unit, showing our new design;

Fig. 2 is a front elevational view of the cosmetic container unit shown in Fig. 1;

Fig. 3 is a top view of the cosmetic container unit shown in Fig. 1; and

Fig. 4 is an expanded view of the cosmetic container unit illustrated in Fig. 1.

We claim:

The ornamental design for a cosmetic container unit, as shown.
